UNITED STATES PATENT OFFICE

1,985,865

CAN OPENING AND SPOUT FORMING DEVICE

Alfred L. Kronquest, Syracuse, N. Y., assignor to
 Continental Can Company, Inc., New York,
 N. Y., a corporation of New York

Application April 23, 1934, Serial No. 722,048

7 Claims. (Cl. 221—23)

The invention relates to new and useful improvements in a can opening and spout forming device which may be utilized for forming a pouring opening in a can end and the shaping of the can body wall so as to provide a pouring spout which is associated with the opening and through which the contents of the can may be dispensed.

Efforts have been made to provide a can with an opening and to shape the body wall adjacent 10 the opening so as to provide a pouring spout. In all such devices, the opening and spout are formed in one operation, or substantially simultaneously, and therefore, it is difficult to operate such a device.

An object of the present invention is to provide 15 a can opening and spout forming device which is so constructed that the can end may be first severed, and after which the body wall of the can shaped to provide a spout.

A further object of the invention is to provide 20 a device of the above type which may be positioned on the can end, and while held in place, the can end severed and the body wall shaped to form the spout.

These and other objects will in part be obvious 25 and will in part be hereinafter more fully disclosed.

In the drawings—

Figure 1 is a side view of a can opening and 30 spout forming device embodying the improvements;

Fig. 2 is a plan view of the same;

Fig. 3 is a sectional view on the line 3—3 of 35 Fig. 1;

Fig. 4 is a view showing the can end severed and the spout forming device positioned for the shaping of the double seam and body wall to provide 40 the spout;

Fig. 5 is a plan view of a portion of the can body 45 showing the end as severed and prior to the shaping of the body wall to form the spout;

Fig. 6 is a view similar to Fig. 4, but showing the spout forming device as having been operated to shape the can wall into a spout;

Fig. 7 is a plan view of the parts shown in Fig. 6, and

Fig. 8 is a plan view showing a portion of the can after the spout has been formed.

The invention resides in a can opening and 50 spout forming device which includes a base member adapted to be positioned on the top of the can so as to rest on the double seam. This base member is provided with offset lugs at opposite sides thereof, and one pair of the lugs engages 55 the double seam at the inner face thereof; while

the other pair of lugs engages the double seam at the outer face thereof, and these lugs, therefore, prevent the base member from moving endwise on the can while it is held in contact therewith. The base member has attached thereto a cutter for severing the can end. This cutter has a depending blade provided with a piercing point and cutting edges diverging from the piercing point. The lugs are placed in contact with the double seam, with the point of the cutter contacting with the can end, and then the base plate is forced to a horizontal position, or into contact with the can end, and this will force the cutter through the can end, severing the can end and rolling the same back so as to form a dispensing opening. The 15 cutter pierces the can end adjacent the double seam, and as it is lowered it will cut the can end along lines extending inwardly from the double seam. After the end has been severed and while the cutter is still in the opening, the spout forming member, which is mounted on the base member, is brought into contact with the double seam at the inner side thereof. This spout forming member has means associated therewith for producing a lateral pressure against the inner face 20 of the double seam so as to force the double seam and the body wall adjacent thereto outward, and thereby form a pouring spout which is associated with the dispensing opening.

Referring more in detail to the drawings, the 25 invention is used for severing a can end and forming a pouring spout. The can body is indicated at 1 in the drawings. The can end 2 is secured to the can body 1 by a double seam 3. This is the usual construction of an hermetically 30 sealed can in which products are marketed. The can may be used for liquid products, and the invention has to do particularly with a can opening and spout forming device for opening a sealed can and preparing the same for dispensing the liquid content thereof. Lubricating oil for 35 automobiles is being marketed in sealed cans of the type above referred to, and the present invention has particularly to do with a device which may be quickly used at the oil filling station or in a garage for opening and preparing the can for the dispensing of the lubricating oil therefrom. The can opening device includes a base member or plate 4 which is of considerably greater length 40 than the diameter of the can. Said base member is provided with offset lugs 5, 5 which are cut from the plate and bent downward, so that when the plate rests on the double seam, these lugs will extend down into the usual recess in the can end and contact with the inner face of the double 45

seam. The plate is also preferably provided with spaced lugs 6, 6 which will engage the outer face of the double seam. The purpose of these lugs is to hold the base member in a fixed longitudinal position and for preventing the base member from sliding endwise on the double seam during the operation of the severing of the can end and the forming of the spout. The base member, as shown in Figures 1 and 2, is provided with another set of lugs 5a, 5a, and an associated set of lugs 6a, 6a which are similar to the lugs 5 and 6. The purpose of the second set of lugs is for use in connection with a can of a larger diameter, as will be referred to more fully hereafter. Fixed to the under side of this base member or plate 4 is a cutter including a shank 7 which is welded or otherwise attached to the base member 4, and a blade 8 which extends substantially at right angles to the base member 4. Said blade 8 is provided with a piercing point 9 (see Fig. 3) and cutting edges 10, 10 which diverge from each other and terminate in the piercing point. When it is desired to open a can, the base member 4 is applied to the can so that the double seam 3 thereof lies between the lugs 5 and 6. This will place the piercing point of the cutting blade in contact with the end close to the double seam at the opposite side of the can body. The operator presses down on the base member, holding the same in contact with the double seam, and also presses down on the outer end of the handle portion 4a which is a part of said base member. This will force the cutter down through the can end, severing the can end along lines extending from the point *a* where the piercing point initially entered the end to the points *b*, *b*, and thence inwardly along substantially parallel lines to the points *c*, *c*. The portion of the metal which is thus cut out is rolled downwardly and inwardly as indicated at 2a. It is the cutting edges 10, 10 which sever the metal along the lines *a*, *b*, and it is the upper portion of the cutter 11 which cuts the metal along the lines *b*, *c* and rolls the same downwardly and inwardly. This forms a free dispensing opening in the can end.

While the cutter is still in the opening, as shown in Fig. 4, the spout forming devices are operated to shape the double seam and the body wall adjacent thereto into a pouring spout. This spout forming device, as shown, consists of a spout shaping member 12 which is pivoted at 13 to a supporting link member 14. This link member 14 is in turn pivoted at 15 to a lug 16 formed from the base member 4. Said base member is severed and the severed portion turned to a vertical position to form this lug 16. The spout forming member 12 carries a finger 17 which is adapted to engage the upper face of the double seam centrally of the opening formed by the cutter. Said spout forming member is also provided with a shoulder 18 which is brought into register with the inner face of the double seam centrally of the opening. There is a spring 19 which is coiled about the pivot 15 securing the link member 14 to the base member 4. One arm of this spring 19 engages underneath the link member 14 and the other arm engages the upper face of the base member 4. This will normally hold the link member 14 raised to a set position, and in this set position, the spout shaping member 12 is set so that the shoulder 18 will be placed just inside the double seam. The upward movement of the member 12 through the action of this spring 19 is limited by a lug 19a. This lug 19a is struck up from the member

12. The member 12 extends through a slot 4b in the base member 4 and the lug 19a is offset to one side as clearly shown in Fig. 7, so that it engages the under face of the base member 4. Mounted on the pivot 13 is a U-shaped plate 20 which serves as a hand rest on which the operator may press to force the joined ends of the link member 14 and the spout forming member 12 downward from the position shown in Fig. 4 to the position shown in Fig. 6. When these members are forced downward, the shoulder 18 will contact with the inner face of the double seam. The lugs 5, 5 will prevent any longitudinal movement of the base member 4, and therefore, the double seam and the can body 15 wall just below the same will be forced outward and shaped into a spout. The double seam is bent outward from the points *d*, *d* to the point *e* which is the end or nose of the spout. This bending of the side wall and the spout outward will contract the portions of the can in the region of the opening formed by the cutter and will distort slightly the side walls *b*, *c* of the opening.

From the above it will be apparent that a can opening and spout forming device has been provided wherein the opening through the can end is formed and completed, after which the parts of the can in the region of the opening are shaped to provide a pouring spout. This distributes the power or force necessary to operate the device so that it may be readily manipulated by hand for the producing of the opening and the forming of the spout.

It is obvious that minor changes in the details of construction and the arrangement of the parts may be made without departing from the spirit of the invention as set forth in the appended claims.

Having thus described the invention, what I claim as new and desire to secure by Letters Patent, is—

1. A can opening and spout forming device comprising a base member, means carried thereby for positioning said base member on the can, a cutting member rigidly attached thereto for severing a can end adjacent the double seam, and means mounted on said base member and operable independently of the cutting member for engaging the can at the inner side of the double seam in the region of the opening for forcing the can wall and the double seam outwardly and shaping the same into a pouring spout.

2. A can opening and spout forming device comprising a base member, said base member having lugs rigidly carried thereby for engaging a can at the opposite sides of the double seam for preventing endwise movement of the base member, a cutting member rigidly attached to said base member and adapted to sever the can end adjacent the double seam at the side of the can opposite from that engaged by the lugs, and means independent of the cutting member for engaging the can at the inner side of the double seam in the region of the opening for forcing the can wall and double seam outwardly and shaping the same into a pouring spout.

3. A can opening and spout forming device comprising a base member, said base member having lugs rigidly carried thereby for engaging a can at the opposite sides of the double seam for preventing endwise movement of the base member, a cutting member rigidly attached to said base

member and adapted to sever the can end adjacent the double seam at the side of the can opposite from that engaged by the lugs, said base member having a slot therethrough disposed centrally 5 of the cutting member, and means operating through said slot and independently of the cutting member for engaging the can at the inner side of the double seam and midway of the opening formed in the end for forcing the can wall 10 and double seam outwardly and shaping the same into a pouring spout.

4. A can opening and spout forming device comprising a base member, said base member having lugs rigidly carried thereby for engaging a can 15 at the opposite sides of the double seam for preventing endwise movement of the base member, a cutting member rigidly attached to said base member and adapted to sever the can end adjacent the double seam at the side of the can opposite from that engaged by the lugs, said base member having a slot disposed centrally of the cutting member, a spout forming member extending 20 through said slot and having a finger adapted to rest on the double seam and a shoulder adapted 25 to engage the double seam at the inner side thereof, and means for moving said spout forming member in an endwise direction for forcing the can wall and the double seam outwardly and shaping the same into a pouring spout.

5. A can opening and spout forming device comprising a base member, said base member having lugs rigidly carried thereby for engaging a can at the opposite sides of the double seam for preventing endwise movement of the base member, 30 a cutting member rigidly attached to said base member and adapted to sever the can end adjacent the double seam at the side of the can opposite from that engaged by the lugs, said base member having a slot disposed centrally of the cutting member, a spout forming member extending through said 35 slot and having a finger adapted to rest on the double seam and a shoulder adapted to engage the inner face of the double seam centrally of the opening formed in the can end, a link to which said spout forming member is attached, means for pivotally attaching said link to said base member adjacent said lugs, a spring adapted to swing 40 said link away from the base member, a lug carried by said spout forming member for limiting the swinging movement of the link, and means carried by said link whereby it may be moved 45 toward the base member for forcing said spout forming member in an endwise direction for shaping the double seam and can wall into a pouring spout.

50 same into a pouring spout.

6. A can opening and spout forming device com-

prising a base member, said base member having lugs rigidly carried thereby for engaging a can at the opposite sides of the double seam for preventing endwise movement of the base member, a cutting member rigidly attached to said base member and adapted to sever the can end adjacent the double seam at the side of the can opposite from that engaged by the lugs, said base member having a slot disposed centrally of the cutting member, a spout forming member extending 10 through said slot and having a finger adapted to rest on the double seam and a shoulder adapted to engage the double seam at the inner side thereof, a link to which said spout forming member is pivoted, said link being pivoted to said base 15 member in the region adjacent the lugs, means whereby said link and spout forming member may be moved toward alinement for forcing the can wall and double seam outwardly and shaping the same into a pouring spout, a spring for 20 moving said link and spout forming member away from said base member, and means for limiting said movement of the link by the spring.

7. A can opening and spout forming device comprising a base member, said base member having lugs rigidly carried thereby for engaging a can 25 at the opposite sides of the double seam for preventing endwise movement of the base member, a cutting member rigidly attached to said base member and adapted to sever the can end adjacent 30 the double seam at the side of the can opposite from that engaged by the lugs, said base member having a slot extending longitudinally thereof and disposed centrally of the cutting member, a spout forming member extending through said 35 slot and having a shoulder adapted to engage the inner face of the double seam centrally of the opening formed in the can end, a link to which said spout forming member is attached, means for pivotally attaching said link to said base member adjacent said lugs, a spring adapted to swing 40 said link away from the base member, a lug carried by said spout forming member for limiting the swinging movement of the link, and means carried by said link whereby it may be moved 45 toward the base member for forcing said spout forming member in an endwise direction for shaping the double seam and can wall into a pouring spout.

ALFRED L. KRONQUEST. 50
